UNITED STATES PATENT OFFICE

KARL SCHMIDT, OF BERLIN-LICHTENRADE, GERMANY, ASSIGNOR TO C. LORENZ
AKTIENGESELLSCHAFT, OF BERLIN-TEMPELHOF, GERMANY

SPEED REGULATOR

Application filed January 5, 1929, Serial No. 330,681, and in Germany January 17, 1928.

This invention relates to speed regulators and more particularly to a speed regulating arrangement for maintaining two rotating bodies in synchronism.

5 An object of the invention is to provide a speed regulator which will maintain substantially constant the speed of a rotating body which may be subjected to sudden heavy changes in load.

10 Heretofore it has been proposed to regulate the speed of a motor for small variations in load or voltage by means of a pair of contacts rotating with and acting upon the field winding of the motor, which contacts operate under action of centrifugal force and 15 gravity to open and close once during each revolution.

According to a feature of the present invention, there is means responsive to a difference in speed of two machines particularly when the machine to be regulated is subjected to a sudden heavy load acts to space contacts whose opening and closure once during each revolution of the controlling machine 25 under the action of centrifugal force and gravity. Thus, the unresponsiveness of machines controlled by such regulators to sudden load or voltage fluctuations can be utilized, and at the same time proper correction 30 made for small changes in the machine speeds, which, although often immeasurably small, must always exist with fluctuations of that kind.

In the accompanying drawing Figs. 1, 2 and 35 3 are diagrammatic perspective views, partly in section, showing a corresponding number of constructional forms of the invention by way of example. The same reference characters in the views refer to constructional or 40 circuit elements of the same kind.

In the arrangement according to Fig. 1, direct current supply leads 1, 2 are connected to a direct current driving motor 3, the speed of which is to be kept synchronous with that 45 of a control motor 4. On the shaft 5 of the motor 3 is a disc 7 arranged in parallel to another disc 8 on the shaft 6 of the motor 4. Between the discs 7 and 8 rotate two friction wheels 9 and 10 which are mounted on a shaft 50 11, so located that the wheels touch the disc

7 but not 8. This shaft 11 is pivoted in two bearings 12 and 13. On the upper end of the shaft 11 is a thread which shifts a contact 15 when shaft 11 is driven. A movable contact 14 is mounted upon the free end of a plate 55 spring, fixed at its opposite end to the disc 8, in such a way that the action of centrifugal force and the force of gravity when the disc rotates at a certain speed momentarily short-circuits the resistance 16 which is connected 60 to the contacts through the slip rings 20. The action of the force of gravity is, in well-known manner, such that the contact is opened and closed once each in a Tirril-like manner on each revolution of the disc 8. (See 65 my U. S. Patent 1,647,020.) Said resistance 16 is located in series with another resistance 17 in the field windings 18 of the motor 3 so as to be entirely or partly influenced by the regulating arrangements described as above. 70 The rotary windings of motor 3 are connected with the slip rings 19 on the motor shaft and direct supplied by 1 and 2.

If the auxiliary machine 4 has a fixed non-varying speed then, so long as the motor 3 75 likewise keeps to this speed, the discs 7 and 8 will remain relative to one another in quietude. If the motor 4, on the other hand, runs faster or slower than its predetermined speed, then friction wheels 9, 10 will be rotated by the disc 7 and change the distance apart of the contacts, and thus the mean opening and closing time of the contacts 14 and 15. In this way the motor receives an additional torque, by varying the field tension 80 through the closed resistance 16, which acts in opposition to the difference of movement, so that the exact synchronous condition is continually maintained.

The same synchronizing action on the 85 speed of the motor can also be produced by variation of the range of regulation, not by changing the distances of the contacts 14 and 15 as described above, but by varying an additional field resistance in the way of a 90 rough regulation, as shown in Fig. 2, so that here also a speed of the motor 3 absolutely synchronous with that of the motor 4 will be maintained.

In the constructional example according 100

to Fig. 2 a variable resistance 21, 22 located in the field current circuit is varied by relative movements of the wheels 9 and 10. The resistance member 21 is herewith connected across slip rings 23 electrically connected with the field-supply 16, 18 of the motor 3. By this means synchronism is always produced while the fast regulator guarantees non-sensitivity to load and voltage fluctuations.

10 The construction according to Fig. 3 differs from Fig. 1 in making the controlling action directly dependent upon the mean opening and closing time of the contacts. This can 15 be done, for example, by means of a small reversible direct current motor 30, which works a rough-regulation in the form of an additional resistance 32 (similar to 21 in Fig. 2). The reversing of the motor is effected by 20 means of the relay 26, which, under the influence of the mean contact current and the mechanical force of a spring 35, closes the armature 27 on the one or the other pole of the battery 33 by contacts 28, 29; whilst the field 25 31 of motor 30 is always excited in the same direction. Other means may be used for varying the resistance 16 in Fig. 3 such as simple relays, differential relays and the like, either alone or in connection with auxiliary 30 motors. Likewise instead of the friction discs and friction wheels mentioned in all the constructional examples, correspondingly constructed ring gears and pinions may be used.

25 What I claim is:

1. Means for maintaining two rotary electrical devices in synchronism comprising a disc rotated by each device, a pair of contacts carried by one of the discs and adapted to 40 open and close during each revolution, a field winding for the device which rotates the other disc and influenced by the opening and closing of said contacts; and a rotary member carried by the contact carrying disc and engaging the other disc and rotated thereby whenever there is a difference in speed of 45 said discs to vary the relative spacing of said contacts.

2. Means for maintaining two rotary electrical devices in synchronism according to 50 claim 1, wherein a resistance in circuit with the field winding is short-circuited by the closing of said contacts.

55 3. Means for maintaining two rotary electrical devices in synchronism according to claim 1 wherein a resistance is in circuit with the field winding, and means responsive to the opening or closure of said contacts for varying said resistance.

In testimony whereof I have affixed my signature.

KARL SCHMIDT.
